BRUSH FOR AUTOMOBILE CHASSIS

Jesse I. Anderson, Indianapolis, Ind., assignor to
 J. I. Holcomb Manufacturing Company,
 Indianapolis, Ind., a corporation

Application May 31, 1933, Serial No. 673,715

7 Claims. (Cl. 15—206)

This invention relates to a brush construction suitable for the cleaning of an automobile chassis, particularly the wheels and running gear of the vehicle.

5 Heretofore in order to clean between the spokes and particularly where the spokes join to the hub of the wheel, it has been necessary to whip-saw rags, or the like, between said spokes at the junction with the hub in order to completely clean 10 the wheel. Tapered brushes have been employed, but these mar the wheel, because the tip was not protected.

The present invention is directed to a tapered brush construction, wherein the tip has a certain 15 cooperating relation with the bristle support of the brush and the end bristles of the brush, so that in the insertion of the brush between the spokes, the paint, enamel or lacquer will not be marred and upon withdrawal of the brush between 20 the spokes, the tip will not become separated from the brush structure, as hereinafter set forth more fully.

This invention also is directed toward a reversible brush.

25 The invention also is directed toward a brush, the shape of which may be readily changed so that the brush support instead of constituting substantially a straight line, may be arched for better operation.

30 The invention also is directed toward a brush of the aforesaid general character previously mentioned, and which is adapted to be readily provided with a handle to transform a handleless brush into a handle type brush.

35 The chief object of the invention is to provide a brush having the foregoing characteristics and which brush is suitable for the purposes before mentioned.

One chief feature of the invention consists in 40 the flexible flange upon the tip whereby upon withdrawal movement of the brush with the tip, the flange turns back upon itself and lies along the tubular portion of the tip so that the full force of withdrawal is not directly applied to the 45 tip for separation of the same from its support, the brush core or body, but the majority of the withdrawal force or opposition to withdrawal is absorbed in the bending of the flange and only a minor portion of that force is transmitted to the tubular portion and this portion is insufficiently effective toward the tendency to separate 50 the entire tip from the brush body support.

The full nature of the invention will be understood from the accompanying drawing and the 55 following description and claims:—

In the drawing, Fig. 1 is a side elevation of a non-reversible type of brush provided with a protective tip.

Fig. 2 is a side elevation of a reversible type of brush, the dotted lines therein representing a 60 detachable handle that has been applied to one end of the brush.

Fig. 3 is an enlarged central sectional view through the tipped end of a brush.

Fig. 4 is a perspective view of the tip.

In the drawing, 10 indicates a substantially cylindrical bristle body supported by a pair of twisted wire portions 11, the bristles being arranged in spiral layer formation. The numeral 12 indicates the tapered spiraled layer portion of 70 the brush which terminates in a projecting wire portion 13—see Fig. 3—and the same constitutes in effect a screw thread arrangement adapted to be seated or screwed into a recess 14 of a rubber cap having the end 15, the tubular portion 16 and 75 the flange portion 17 adjacent the mouth of the opening in portion 16. In Fig. 3, as shown clearly, the flange on the tip is seated on the projecting end 13 of the wire portions 11 and to such a depth that the bristles 18 at the end of the brush are 80 compressed and turned back toward the cylindrical portion of the brush.

In the form of the invention shown in Fig. 1, there also is mounted upon the projecting ends 85 of the wire portions 11 a flange or guard disc 19 which, in the present instance, may be fibre, and the handle 20 includes a bore 21 therein which receives the projecting wire portion ends 22. One of the wire portions is extended, in the present instance, to the end of the brush and is turned 90 outwardly and is seated in a slot 23 and 24, so that the end 25 and the lateral portion 26 seat respectively in the slotted portion 24 and 23—see Fig. 1. The aforesaid constitutes the single brush 95 construction embodying the invention.

In Fig. 2 there is illustrated a modified and preferred form of the invention and herein the brush is of the reversible type. The cylindrical body of the brush is indicated by the numeral 30 and the bristle support consists of two twisted relatively 100 rigid wire portions 31. The cylindrical body portion 30 of the brush is extended as tapered portions 32 and 33 at opposite ends and each terminate short of the extreme ends of the wire portion 31 and upon the latter at 35 and 36 is mounted in substantially the same manner as illustrated in Fig. 3, the protective tip shown in perspective in Fig. 4. The same bristle and flange cooperation exists. The tip in all instances is prefer- 105 110

ably formed of rubber and the flange thereof is relatively resilient.

The brush is initially made with the wire portions 31 substantially in a straight line, the bristles being arranged or mounted by said wire portions in spiral formation, which is old in the industry. The brush shown in Fig. 2 has been forcibly deformed so that it may be readily applied to the spaces between the spokes at the junction of the 10 spokes with the hub in a wheel construction and in such other places as cannot be readily cleaned by a sponge or standard brush construction.

Whenever it is desired to use a handle brush arrangement with the brush shown in Fig. 2, all 15 that is necessary is to take a 6 to 8" piece of $\frac{5}{8}$ " or $\frac{3}{4}$ " rubber hose, indicated at 37, and by the dotted lines in Fig. 2, and having the bore 38, and telescope the same over one end of the brush. Such 20 telescopic movement continues until the hose assumes the position on the brush as indicated by the transverse line 39. This provides a detachable handle for the reversible brush and the brush will function with this handle in exactly the same manner as the brush shown in Fig. 1. To separate 25 the hose from the brush, the two are caused to rotate relatively of each other accompanied by a withdrawal movement, which enacts with the radially extending bristles to release them from locking engagement with the interior of the hose.

30 Any other suitable tubular handle or a handle having a bore, may be utilized. In this connection, however, it is noted that the flange of the tip 36 constitutes a support for the end bristles in approximately the same manner that the flange 35 19 constitutes a support for the end bristles in the form of the invention shown in Fig. 1.

While the invention has been described in great detail in the foregoing specification, the same is to be considered as illustrative and not restrictive 40 in character and the modifications disclosed hereinbefore as well as others which will readily suggest themselves to persons skilled in this art, are all considered to be within the broad scope of the invention, reference being had to the appended claims.

The invention claimed is:—

1. In a brush construction, a brush body comprising bristles circularly and longitudinally arranged, one end of the body having bristles of shorter length than the body portion to form a tapered end, a pair of twisted wire portions constituting the support for said bristles and projecting at each end beyond the brush body, and a rubber tip having an elongated body of lesser diameter than the tapered end and having a bore therein to nest therein the projecting twisted wire portions adjacent the tapered end, the projecting twisted wire portions at one end consti-

tuting a threaded connection and the sole connection anchorage for the tip.

2. In a brush construction, a brush body comprising bristles circularly and longitudinally arranged, one end of the body having bristles of shorter length than the body portion to form a tapered end, a pair of twisted wire portions constituting the support for said bristles and projecting at each end beyond the brush body, and a rubber tip of lesser diameter than the tapered end and having a single bore therein with a single opening and secured to the projecting wire portions adjacent the tapered end, the projecting wire portions at one end constituting a threaded connection for the tip, said tip including a lateral flexible flange projecting therefrom adjacent the opening and bearing against the end bristles for mutual reenforcement and bristle protection in brush withdrawal movement.

3. A device as defined by claim 2, characterized by the brush being of reversible character, to wit, the opposite ends of the brush being similarly tapered and similarly tipped.

4. A device as defined by claim 1, characterized by the addition of a handle member having a bore therein and adapted to receive the opposite projecting end of the bristle support, said handle member consisting of a suitable length of tubular hose.

5. A device as defined by claim 2, characterized by the addition of a handle member having a bore therein and adapted to receive the opposite projecting end of the bristle support, said handle member consisting of a suitable length of tubular hose.

6. A device as defined by claim 1, characterized by the brush being of reversible character, to wit, the opposite ends of the brush being similarly tapered and similarly tipped, and a handle member having a bore therein and adapted to receive the opposite projecting end of the bristle support, said handle member consisting of a suitable length of tubular hose telescoped over the said opposite end of the bristle support and the tip thereon.

7. A device as defined by claim 1, characterized by the brush being of reversible character, to wit, the opposite ends of the brush being similarly tapered and similarly tipped, and a handle member having a bore therein and adapted to receive the opposite projecting end of the bristle support, said handle member consisting of a suitable length of tubular hose telescoped over the said opposite end of the bristle support and the tip thereon, the flange of the tip upon the said opposite end cooperating with said hose handle for the purpose set forth.
